FIG. 1

FIG. 2

INVENTOR

IRA JACOBS

or Wright & Chan

ATTYS.

UNITED STATES PATENT OFFICE.

IRA JACOBS, OF SAN FRANCISCO, CALIFORNIA.

DESIGN FOR A CANDY BAR.

60,147.

Specification for Design.

Patented Jan. 3, 1922.

Application filed August 29, 1921. Serial No. 496,723. Term of patent 7 years.

To all whom it may concern:

Be it known that I, IRA JACOBS, a citizen of the United States, residing at San Francisco, in the county of San Francisco and State of California, have invented a new, original, and ornamental Design for Candy Bars, of which the following is a specification, reference being had to the accompanying drawing, forming part thereof.

Figure 1 is a plan view and Figure 2 is a rear elevation of a candy bar showing my new design.

I claim:

The ornamental design for a candy bar as shown.

August 23, 1921.

IRA JACOBS.
